John W. Vandiver

UNITED STATES PATENT OFFICE.

JOHN W. VANDIVER, OF SHELBINA, MISSOURI.

IMPROVEMENT IN CORN-PLANTERS.

Specification forming part of Letters Patent No. 40,202, dated October 6, 1863.

To all whom it may concern:

Be it known that I, JOHN W. VANDIVER, of Shelbina, in the county of Shelby and State of Missouri, have invented a new and Improved Seeding-Machine; and I do hereby declare that the following is a full, clear, and exact description of the same, reference being had to the accompanying drawings, making a part of this specification, in which—

Figure 1 is a front end elevation of a machine embodying my invention. Fig. 2 is a longitudinal sectional elevation of the same in line *xx* of Fig. 1. Fig. 3 is a plan or top view of Fig. 1. Fig. 4 is a detached sectional view of one of the hoppers, seed-conducting tubes, and accessories, the section being taken in the line *yy* of Fig. 3. Fig. 5 is a detached sectional view of the same, taken in the line *zz* of Fig. 3. Fig. 6 is a horizontal section of a seed-conducting tube, taken in the line *11* of Figs. 4 and 5, looking down. Fig. 7 is a similar view of the same in line *22* of Figs. 4 and 5, looking down.

Similar letters of reference indicate corresponding parts in the several views.

The object of this invention is to obtain a machine which may be readily adapted and with like efficiency for planting in either new or old ground; and it consists in certain novel devices and combinations, hereinafter fully explained.

To enable others skilled in the art to which my invention appertains to fully understand and construct the same, I will proceed to describe it.

A and B in Figs. 2 and 3 represent two parts of a frame, which is mounted in front on a pair of runners, C, and in the rear on a pair of wheels, D, the peripheries of which latter are of concave form. The two parts of the frame are connected together by pivots or bolts *a'*, so that they are free to rise and fall or move independently of each other in a vertical direction. The runners C, besides carrying the forward end of the frame, serve also to form the furrows in the ground for the seed, and for this purpose they are furnished in front with a sharp cutting-edge, and at their rear end with two outwardly-flaring wings, the former to penetrate and the latter to open the soil.

On the rear part of the forward section, A, of the frame, at each side, a seed-box, E, is

placed, and depending from this seed-box and connecting at its lower end with the outwardly-flaring wings of the runner is a seed-conducting tube, F, which may be in the form represented in the accompanying drawings, or of any other suitable form. The bottom of each seed-box E has an opening made in it corresponding with the opening in the conducting-tube F. Adapted to slide over this opening between guides in the bottom of the seed-box is a short metal slide, *a*, which has two round holes made in it at equal distances from a transverse slot which passes through the slide, and is adapted to receive the upper end of a forked bar or valve, which is arranged in each of the seed-conducting tubes F. Each of the metal slides *a* work beneath a metal plate, *b*, which is confined at its ends, and provided on each side of a central cross-bar, *c*, with an oblong rectangular opening, alternately through which the seed passes from the hopper into the round holes of the metal slide *a* as they are exposed. The cross-bar *c* has a strip of india-rubber or other suitable material bent over it and secured so as to have its lower edges rest upon the metal slide *a* for the purpose of removing the surplus grain from the slide as it is moved over the conducting-tube to deposit the seed contained in its seed-openings into the ground. The slides *a* of both of the seed-boxes E are connected together by a bar, *H*, which has two holes made in it, equidistant from the center, to receive the lower end of a hand-lever, I, by means of which the attendant, riding on the forward part of the machine, is enabled to move the seed-slides *a* in both hoppers simultaneously. The lever I has its fulcrum in one of two holes in the seat J, in either of which holes it may be placed, according as it is desired to operate the dropping mechanism with the right or left hand.

In each conducting-tube F an upright bar, *d*, forked at its lower end, is pivoted at *S* and connected at its upper end with the seed-slide *a*, from which it receives an oscillating motion, in manner clearly shown in Figs. 4 and 5.

Below the forked end of the upright bar or valve *d* strips of metal or tongues *e* are attached—one to each side of the tube F in a central position. These tongues are slightly bent inward at their lower ends, and occupy but a little space in the center of each side of the

tube, as clearly shown in Figs. 5 and 7, for the purpose hereinafter explained.

To each side of a standard, K, depending from the frame A, a bar, f, terminating at its rear end in a covering-share, g, is attached by a pivot, i, and the rear ends of the bars f of each tube are connected by a cross-bar, j, and suspended by a link or rod, k, from the outer end of a lever, l, which is fulcrumed at its inner end to the frame A. The levers l, about midway of their length, are each connected to another lever, m, which stands at right angles to it, and these levers m are pivoted at their forward end to the seed-hoppers, and extend back to within convenient reach of a person sitting on the seat of the frame B. The longitudinal pieces of the forward section, A, of the main frame project some distance behind the hopper E, and form scrapers for removing dirt or weeds adhering to the outside of the covering-shares g.

Attached to opposite ends of a shaft, L, which is supported in suitable boxes on the back part of the frame B, are two scrapers, n, adapted to conform to the concavity of the peripheries of the wheels. When not required for use these scrapers n may be turned back out of the way by the driver by means of an arm, M, which projects from the shaft L.

The machine above described is adapted for planting in old ground.

To adapt the same machine for planting in new or sod ground I attach a cutter, N, of the form represented in Figs. 4 and 5, to the bottom of the runners C by bolts o and p, as shown clearly by dotted lines in Fig. 2, and fill in the space between the flaring wings of the runners and wings q, terminating the rear portion of the cutter N, with strips of wood r, which may be attached by a screw passing through the shell of the conducting-tubes, or in any other suitable manner. These strips of wood r are designed simply to prevent the seed descending the conducting-tubes from falling outside of the cutter when planting in sod-ground. The only other change necessary in the machine to adapt it for planting in sod-ground is to hoop the wheels. This is done by tires made in two or more parts, which are secured to the wheels by bolts passing through the felloes of the same, as clearly shown by dotted lines in Fig. 2. The object in having these tires on the wheels is to roll the sod flat after the seed is deposited in the ground.

The operation is as follows: As the machine is drawn along over the ground an attendant on the front part of the frame A operates the lever I back and forth, and said lever, through the medium of the connecting-rod H, gives a reciprocating motion to the slides a and the seed is distributed from the seed-boxes E alternately through the holes in the slides a into

the conducting-tubes F, thence into the ground. As the seed from each opening in the slide a descends in the conducting-tube F it is caught between the forked end of the valve d and tube F and retained in that position until the slide a is moved in the opposite direction, when it is released by the valves moving to the opposite side of the tube, a portion of the seed falls on each side of the tongue directly into the furrow made by the runners, and another portion falls onto the tongue and is glanced to the opposite side of the tube, and as the valves are attached at their upper ends to the slides a they will vibrate and the seed that passes down between them and the metal strips or tongues e will be discharged at opposite sides of the tube, and the seed of each dropping scattered in the hills. The scattering of the seed in the hills is very important, as each stalk has sufficient room to expand and grow properly, the roots being kept comparatively free from its fellows in the same hill. The shares cover the seed and the roller compresses the earth on the same in rounded form.

Having thus described my invention, what I claim as new, and desire to secure by Letters Patent, is—

1. Constructing the frame A so that the longitudinal beams thereof shall form scrapers for the hinged coverer-shares g, in the manner described.

2. The combination of the hinged coverers g with the levers l and m, when arranged as described, so that a person riding upon the rear part of the frame is enabled to raise or lower the coverers on both sides of the machine independent of one another and of the runners, in the manner specified.

3. The forked bars or valves d, pivoted within the seed-conducting tubes F and connected with the seed-distributing slides a, in combination with the metal strips or tongues e, attached on opposite sides and below the valve to the inner sides of the conducting-tubes F, substantially as and for the purposes set forth.

4. Fitting a rim or tire to the wheels of a corn-planter in sections, so that it can be put on or taken off, according as a flat or concave tread is needed to adapt the machine for planting in sod or old ground, in the manner and for the purpose specified.

5. The detachable sod-cutters N, attached by means of bolts o p to the runners C, in combination with the same, and the wooden strips r in the seed-conducting tube F, in the manner and for the purpose specified.

JOHN W. VANDIVER.
